FUEL BURNER SYSTEM

Robert L. Harris and Marcus Lothrop, Berkeley, Calif., assignors to Yuba Manufacturing Company, San Francisco, Calif., a corporation of California

Application May 17, 1948, Serial No. 27,374

14 Claims. (Cl. 158—36.4)

1

Our invention relates to means especially useful in handling liquid fuel atomized in an air stream.

Our invention pertains to burners in which the amount of fuel burned varies from time to time over a relatively wide range and particularly to burners utilizing pressure atomization to break up liquid fuel into readily combustible droplets. As an example, it can be assumed that a minimum atomization pressure is one hundred pounds per square inch and that the amount of fuel ranges from a predetermined minimum amount to a maximum eight times that amount. The proportional increase in fuel discharged from a nozzle is equal to the square root of the proportional increase in pressure. So, for a quantity range of eight the pressure must be increased sixty-four fold. The hundred pound per square inch minimum pressure necessary for atomization must be raised to 6400 pounds per square inch. In any ordinary, commercial sense, the pressure required is prohibitive.

As an alternative to building the system to stand this pressure, the maximum amount of oil or fuel can be pumped and all but the amount instantaneously utilized can be by-passed. Eight times the amount of fuel burned must necessarily be pumped even if only a minimum fire is required. Another alternative is to provide a nozzle operating at substantially a uniform pressure but varying automatically in area. Such nozzles are theoretically possible but are practically either prohibitively expensive or are not normally workable under the usual, rough conditions of operation.

It is therefore, an object of our invention to provide a fuel burning system in which the necessary atomization pressure is sustained, the range in amount of fuel discharged is relatively wide and in which a relatively simple nozzle and moderate pressures are utilized.

Another object of the invention is to provide a means for metering fuel over a relatively wide quantity range.

An additional object of the invention is to provide a fuel burning system quickly responsive to variations in demand.

Another object of the invention is to provide a fuel burning system which meters the fuel accurately yet requires only a simple regulating mechanism.

A further object of the invention is to provide a fuel burning system capable of sustained, consistent operation.

An additional object of the invention is to pro-

2

vide a basic fuel burning system which readily lends itself to sundry adjustments and refinements.

An additional object of the invention is to provide a fuel burning system readily adjustable when installed or when in use to vary the characteristics of the system as desired.

A still further object of the invention is to provide a fuel burning system capable of meeting closely the requirements for combustion of widely varying quantities of fuel.

Other objects together with the foregoing are attained in the embodiment of the invention described in the accompanying description and illustrated in the accompanying drawings in which

Figure 1 is an isometric view in diagrammatic form of a fuel burning system constructed in accordance with our invention, portions being broken away to disclose interior construction.

Figure 2 is a cross-section through a fuel metering valve utilized in our system, the plane of section generally being a median, vertical plane.

Figure 3 is a cross-section similar to Figure 2 but taken on the planes indicated by the lines 25 3—3 of Figure 2.

Figure 4 is a cross-section generally on a median, longitudinal plane through a fuel nozzle utilized in connection with our fuel burning system.

In its preferred form our fuel burning system comprises a differential pressure nozzle connected by a conduit to a fuel pump driven at a speed variable substantially in accordance with the demand upon the fuel burning system. The conduit is provided with a means for releasing surplus fuel actuated automatically to vary the pressure upon the nozzle to provide the requisite output.

After a predetermined rate of discharge from the nozzle is attained, a second nozzle is introduced to the system and subsequently the pressure is varied on both of the nozzles working together.

Additional nozzles are included in the system as the amount of discharge increases with the pressure on all of the nozzles being concurrently regulated.

While our fuel burning system is susceptible to formulation in many different ways largely dependent upon the particular installation, it has been successfully embodied as shown herein. It is illustrated by an example utilizing a minimum atomizing pressure of one hundred pounds per square inch on fuel oil of approximately thirty-two degrees gravity and with a quantity range 55 from a minimum of four gallons per hour to a

maximum of thirty-two gallons per hour. This mechanism is utilized in connection with the steam power plant disclosed more completely in our co-pending application entitled "Steam Power Plant," filed May 1, 1948, Serial No. 24,656. In that power plant, an internal combustion engine drives not only an air blower but also a fuel pump for expelling the fuel through a nozzle to mix with the air.

In the present illustration, the speed of the driving mechanism 6 is regulated by a manually controlled handle 7 so that the speed of the driven blower (not shown) is correspondingly controlled. The engine 6 also is effective through a drive shaft 8 to impel a positive displacement fuel pump 9, the speed of which corresponds to that of the engine. The inlet of the pump is joined by a conduit 11 to an atmospheric pressure tank 12 containing a body 13 of fuel such as oil. The pump discharges the fuel through a conduit 14 at any pressure within the capacity of the pump, a range of several hundred pounds. The discharged fuel flows into a valve 16 effective in one position to divert the fuel through a return conduit 17 to the tank 12. In this valve position, the pump 9 merely recirculates the fuel oil. The valve 16, in another position, directs the pumped fuel into a conducting line 19 leading to a fuel oil valve generally designated 21. Within the valve 21 the fuel is regulated and distributed, any excess being returned to the tank 12.

The valve 21 is comprised of a casing 22 including a block 23 secured by fastenings 24 to a base 26. The block 23 is provided with a transverse bore 27 into which the line 19 extends. The bore 27 is therefore supplied with fuel under pressure from the pump 9 whenever the valve 16 is so directed. Oil supplied to the bore 27 is free to enter a vertical passage 28 and from it to enter a cross bore 29 from which a conduit 31 extends to a first nozzle 32.

The nozzle 32 includes a body 33 having a bore 34 communicating with the conduit 31. The bore also merges with a passage 36 terminating in an annular groove 37 concentric with the axis 38 of the nozzle. In an enlarged bore 39 is disposed a plug 41 firmly clamping a flexible diaphragm 42 in position overlying the groove 37. The diaphragm also overlies an axial bore 43 extending to a receptacle 44 in which a standard nozzle tip 46 is screwed. The nozzle tip is of the sort usually available for oil burners and includes not only a filter screen but also passageways for tangentially directing the fuel into an internal chamber from which the fuel spins out through a central discharge orifice 47 in a fine spray. The nozzle tip 46 is rated to discharge a set amount of fuel, say four gallons per hour, at a standard atomizing pressure of one hundred pounds per square inch.

When pressure is exerted by fuel in the annulus 37 upon the diaphragm 42, the diaphragm is displaced toward the left in Figure 4 and the fuel flows from the annulus into the central passage 43. When the diaphragm is displaced it is unseated from an annular seat 48 and its effective area is suddenly increased. The pressure, effective upon a suddenly augmented area, abruptly lifts the diaphragm from its sealing position and opens the passage 43. Thus, while an increase in pressure against the diaphragm 42 may be relatively gradual, as soon as it barely unseats the diaphragm, it quickly accomplishes the remaining diaphragm movement so that the flow of fuel to the nozzle tip under full pressure is

initiated abruptly. Correspondingly, even though the pressure of the supplied fuel in the passageway 36 decreases gradually, as soon as the diaphragm 42 begins to seat, the area available to the pressure is abruptly reduced so that the diaphragm then quickly blocks the passageway 43. The fuel still under a moderately high pressure a little below the opening pressure is retained within the conduit 31 while the fuel remaining within the passage 43 and the chamber of the nozzle tip 46 falls to atmospheric pressure.

Since such fuel is usually gassy, it foams and expands and continues to discharge from the orifice 47 while its pressure is reducing. The abrupt seating of the diaphragm traps all of the oil in the line 19 under a moderately high pressure, no matter how long the line nor the amount of oil, and leaves so little expanding fuel within the remaining passageways that little if any fuel dribbles from the nozzle tip 46. Thus the nozzle both at starting and at stopping so quickly discharges either not at all or at substantially one hundred pounds per square inch pressure that all of the ejected fuel is appropriately atomized and there is little or no intermediate pressure operation with resulting poor atomization and dribbling of the fuel.

To assist the diaphragm 42 in its operations and to provide an appropriate setting or adjustment for the pressure response of the diaphragm, the plug 41 carries a piston 51 abutting and pressed by a spring 52 against the diaphragm. A cap 53 open to the atmosphere by means of a hole 54 engages the plug 41 and is screwed to a position so that the spring provides an appropriate opening pressure and a corresponding closing pressure. Since the opening and closing pressures are different because of the different areas of the diaphragm available at the opening and closing events, the nozzle 32 as a whole is characterized as a differential pressure nozzle.

As the fuel from the engine driven pump flows in through the bore 27 and the connecting passageways 28 and 29 to the nozzle 32, the nozzle opens at, say, one hundred pounds per square inch pressure and supplies fuel to the air stream from the engine driven blower. Though the oil pump and the air pump are simultaneously driven, the amount of fuel which issues from the nozzle is correctly proportioned to the air only at one particular condition or speed of operation. To avoid pumping many times the required amount but to make sure that there is no deficiency of fuel, we drive the pump 9 to provide a small excess capacity, and then by-pass the small amount of excess fuel. This affords compensation for any possible long term drop in efficiency of the fuel pump 9 or in other leakages or discrepancies in the system.

As part of the by-pass mechanism, there is screwed into the block 23 to form a continuation of the passage 28, a tube 56 carrying a shield 57 screwed on it. The shield serves as a confining member for a poppet valve 58 urged onto an annular seat 59 at the end of the tube 56 by a helical spring 61. When the valve 58 is tight against its seat 59, no fuel can flow from the passageway 29 through the central passage of the tube as a shunt path from the nozzle 32, but when the valve 58 is unseated, fuel can escape through it from the passageway 29 and so by-pass the nozzle 32. By-passed fuel flows through apertures 62 in the shield into a central chamber 63 of the housing base 26 from which it passes through a channel 64 into a cam chamber 66 and from that

chamber through a drain pipe 67 at substantially atmospheric pressure back to the tank 12. By regulating the pressure exerted by the spring 61, the valve 58 is correspondingly pressed tightly or loosely against its seat 59 and either precludes the by-pass flow of fuel from the nozzle passage 29 or regulates the amount of fuel by-passed and correspondingly the remaining amount of fuel expelled from the nozzle.

To operate the by-pass spring 61, there is provided an adjusting screw 68 engaging the lower end of the spring and held by a lock nut 69 in adjusted position in a cam follower 71 operable in a cylinder 72 in the base 26 between the chamber 63 and the chamber 66. The follower 71 is prevented from rotating by a set screw 73 but is freely reciprocable in accordance with the contour of a first cam 74 disposed within the cam chamber 66 and held on an operating shaft 76 by a set screw 77. The shaft 76 is mounted in bearings 78 and 79 in the base 26 and is rotatable by an external lever 80. Oil leakage from the housing chamber 66 is precluded by a shaft seal 81 and by a cap 82. A rod 83 pivotally joins the lever 80 and the operating lever 7.

The operating lever, being effective to control the general operation of the driving motor 6 and correspondingly the speed of the air blower and of the pump 9, is likewise effective almost simultaneously to rotate the shaft 76 and to revolve the first cam 74. The cam is provided with an actuating surface 84, the portion having an angular extent between a center line 85 and a center line 86 constituting what is termed a "first range." When the cam follower is in the position shown in Figure 3, the screw 68 is adjusted and locked in a position such that the pressure of the spring 61 permits sufficient fuel to by-pass the valve 58 so that the remaining amount of fuel discharges from the first nozzle 32 at one hundred pounds per square inch. This affords the minimum quantity of four gallons per hour. As the lever 7 is operated to increase the speed of the engine 6 and of the pump 9 and of the air blower, the output of the pump 9 is not necessarily increased in proportion to the output of the air blower. Normally, the relationship is not a simple proportion. To obtain the proper fuel-air proportions at different speeds, different amounts of fuel must be by-passed by the valve 58 at different speeds.

Accordingly, the contour of the first range of the cam surface 84 is made such that in each position of rotation of the cam in response to operation of the lever 7, the pressure of the spring 61 is correspondingly varied to govern the amount of fuel by-passed. There is thus left for discharge through the first nozzle 32 an amount of fuel exactly proportional to the amount of air available for combustion. The proportionate amount of fuel is readily changed, if desired, to meet varying conditions either by changing the adjustment of the screw 68, by substituting a spring 61 of different characteristics, by replacing the first cam 74 as a whole, or by varying the shape of the surface 84 exactly to produce the desired results. Since the first nozzle 32 is usually utilized in starting combustion, a somewhat rich mixture, that is, one having a high proportion of fuel to air, is initially provided by slightly increasing the radius of the initial part of the surface 84.

As the spring 61 is compressed as the cam rotates, the pressure of the fuel supplied to the first nozzle 32 is continually increased until it reaches a predetermined value, say, four hundred pounds

per square inch. The amount of fuel discharged from the nozzle when supplied at four hundred pounds per square inch pressure is approximately twice the amount of fuel discharged when the supply is only at one hundred pounds per square inch pressure. That is, for a typical nozzle, the discharge at four hundred pounds per square inch supply pressure is approximately eight gallons per hour if the discharge at the standard one hundred pounds per square inch supply pressure is the rated four gallons per hour. As four hundred pounds per square inch pressure is about as high as it is desired to operate the system, we provide means for continuing the increase in output without exceeding this pressure.

For that reason a second nozzle 91 is abruptly introduced into the system. The nozzle 91 is identical with the nozzle 32 and is of a similar rating, that is to say, four gallons per hour discharge at one hundred pounds per square inch supply pressure. It is joined by a conduit 92 to the block 23 of the fuel valve, communicating through an opening 93. This passageway is intersected by a bore 94 provided with a valve seat member 96. On this is normally disposed a ball valve 97 held on its seat by a coil spring 98 received within a closure cap 99 screwed into the block 23. Communication between the bore 27 and the passage 93 is normally prevented as the ball 97 is held on the seat partly by the spring 98 but largely by the unbalanced fuel pressure exerted thereon, since the chamber 63 is about at atmospheric pressure. To dislodge the ball and permit communication, the bore 94 is narrowed and threaded to receive a sleeve 101 carrying packing 102 and a packing nut 103 at its lower end and providing a very close sliding fit for a rod 104. This terminates near the ball 97 and extends from the packing nut 103 to contact an adjusting screw 106 locked by a nut 107 in position in the cam follower 71.

During the fore part of the motion of the cam 74 in its first range, there is sufficient clearance between the upper end of the rod 104 and the ball 97 so that the ball remains seated and prevents fuel flow into the passage 93. However, just before the cam surface 84 compresses the spring 61 to produce a discharge pressure of approximately four hundred pounds per square inch for the first nozzle 32, the same cam surface or substantially the same contour of the cam having gradually lifted the rod 104 against the ball 97, is finally effective to dislodge the ball abruptly from its seat member 96. The linear motion required to move the ball from its flow blocking to its flow permitting position is very slight. Since this is a small fraction of the total deflection of the spring 61, there is only a small change in the spring controlled pressure as the ball 97 is dislodged.

The adjustments are made in such a fashion (preferably by pressure gage in the conduit 14) that at the time the pressure within the nozzle 32 is four hundred pounds per square inch, the ball 97 is dislodged to provide an additional path for the fuel through the passage 93 to the second nozzle 91. The pressure immediately drops to approximately one hundred pounds per square inch due to the added outlet and to another bypass regulator presently described. Abruptly, the fuel discharges from two nozzles at a supply pressure of one hundred pounds per square inch whereas immediately before it had been discharging from one nozzle at a supply pressure of four hundred pounds per square inch. Since

the two nozzles are substantially the same size and since each of them discharges four gallons per hour at one hundred pounds pressure whereas the first nozzle discharged eight gallons per hour at four hundred pounds pressure, the total discharge remains eight gallons per hour but the supply pressure is reduced to the original value.

Because of the substantially similar characteristics of the nozzles, the transition in discharge from one nozzle at a supply pressure of four hundred pounds per square inch to two nozzles at a supply pressure of one hundred pounds per square inch is not particularly critical and is rather smoothly made, very little difference being detectable in the resulting combustion. While there is some difference in fineness of atomization, still this is always above the minimum satisfactory value, and turbulence of the air-fuel mixture makes this difference inconsequential.

When the demand drops and the lever 1 is reversed in its movement to reduce the output, the second nozzle 91 is immediately cut out of operation by the reseating of the valve 97 as the pin 104 is dropped and the ball 97 reseated due to return of the cam 74. The spring 61 being substantially at its previous position, the pressure is restored immediately to four hundred pounds per square inch and is so supplied to the first nozzle 32.

The surface 108 of the cam 74 between the center line 86 and a center line 109 defines the second range of operation. In this range, the surface 108 is substantially circular so that the spring 61 is maintained at its condition of four hundred pounds pressure. The transition of the cam between the first range surface 84 and the second range surface 108 is rather abrupt and because of the spring pressure against the cam and because of the unbalanced pressure tending to hold the ball 97 seated, the cam does not tend to stay exactly poised between the first range and the second range conditions. Rather, adjacent the transition point the pressure reacting on the cam changes so abruptly that the cam tends to remain either just on one side of the transition point in its first range or just on the other side of the transition point in its second range. This property is permitted by a slight play or looseness or elasticity in the lever system especially in the fitting of the rod 83 so that in normal practice either one nozzle or two nozzles are in operation. There is nothing more than an instantaneous and harmless passage of the system through the intermediate, transition position. The nozzles are not irregularly or unstably cut into and out of operation.

When two nozzles are in circuit, the first bypass regulator is ineffective. This is because the cam surface 108 holds the by-pass valve 58 seated below 400 pounds per square inch pressure while the unseating of the ball 97 opens a parallel flow path to the second nozzle 91. With the additional outlet open, the pressure drops below 400 pounds per square inch pressure and the first regulator closes completely and is therefore ineffective. To regulate the pressure under these conditions, there is provided a second pressure regulator 111 in construction identical with the first pressure regulator and including a valve like the valve 58. The second regulator 111 has its own spring 112 supported by a screw 113 mounted in a second cam follower 114 reciprocable between the chambers 63 and 66 in the base 26. The follower 114 rides upon

6 a second cam 116 mounted on the shaft 76 and turning in unison with the cam 74. While the initial cam surface is circular, the central, inclined portion 117 of the surface of the cam 116 is shaped as illustrated by a dotted line in Figure 3 and is so contoured as to control the pressure of the fuel supplied to both the nozzles 32 and 91 when they are both in operation. Their supply pressure is appropriately increased from one hundred to four hundred pounds per square inch. Because this surface 117 is entirely distinct from the surface 84 or from the circular surface 108, the characteristics of discharge of the two nozzles for an intermediate range of operation can be independently coordinated with the requirements of the system as a whole, especially the output of the blower supplying the combustion air. On both sides of its range of effectiveness, the cam 116 is circular so that the valve holds its initial or final position.

10 The cam follower 114 near the upper end of the cam's effective range acuates a rod 119 to unseat a ball valve 121 in the fashion the ball valve 97 is unseated. This permits communication from the bore 27 into a conduit 122 leading to a third nozzle 123 and through a branch conduit 124 to a fourth nozzle 126. The nozzles 123 and 126 are identical with the nozzle 32.

15 20 A single nozzle 123 of substantially double the rating or capacity of the remaining nozzles can be utilized but for interchangeability of parts it is preferred to provide two final nozzles.

25 The output of nozzles 32 and 91 at the final supply pressure of four hundred pounds per square inch, the pressure at which the valve 121 opens, is approximately double their initial output or sixteen gallons per hour. If, then, the pressure is reduced again to one hundred pounds per square inch, it requires four of the four gallon per hour nozzles to produce the equivalent sixteen gallons per hour output. The pressure effective on all four of the nozzles after the valve 121 has been opened by the rod 119 is regulated by a valve mechanism 127 identical with that of the regulator valve 58. It is operated by a spring 128 responsive through an adjusting screw 129 to a third cam follower 131 reciprocated within the base 26 between the chambers 63 and 66 by a third cam 132 fast on the shaft 76.

30 35 40 The effective regulating surface of the cam 132 is illustrated by the dotted line 133 in Figure 3. Outside this range, the initial portions of the cam 132 are circular. This cam is not effective in the first range nor in the second range but is effective in a third range between the center line 109 and a center line 134.

45 50 55 The transition from the second range to the third range is abrupt as previously described in connection with the transition from the first range to the second range. Either two nozzles are operating at four hundred pounds per square inch pressure or four nozzles are operating at one hundred pounds per square inch pressure and the mechanism hesitates imperceptibly between such ranges. As the lever 1 is moved to its maximum operation position, the cam 132 gradually increases the compression of the spring 128 and, by reducing the amount of bypassed fuel, gradually increases the pressure of the fuel supplied to all the nozzles from its initial one hundred pounds per square inch value to a final value of approximately four hundred pounds per square inch. During this time, the valve 58 and the regulator 112 are held closed.

60 65 70 75 80

in their four hundred pound per square inch positions or substantially so.

When the valve is effective to maintain substantially four hundred pounds per square inch pressure on all four of the nozzles, there is produced a total output of about thirty-two gallons of fuel per hour, the desired maximum. This is accomplished with a pressure range of four rather than sixty-four, and by pumping only say five or ten percent more oil than atomized rather than up to eight hundred percent more oil than atomized.

This mechanism can be added to with as many units as necessary to cut additional nozzles into the burner to produce as wide a range as necessary, each nozzle or group of nozzles being added to the preceding, effective ones and the pressure of the effective group being boosted through a relatively narrow range and then dropped as additional nozzles are introduced. The reverse process takes place as the capacity of the burner is reduced, certain nozzles or groups being periodically eliminated with simultaneous pressure compensation.

While the set-up as described is effective for all normal operations, it is sometimes desired to change the general ratio of fuel to air as an over-all adjustment rather than individually changing portions of the contour of the cam surfaces, in addition to or in lieu of making adjustments by the screws, such as 113 and 129. A general adjustment to compensate for different air weights at different altitudes, for example, or where a markedly different type of fuel is used can readily be accomplished by shortening or lengthening the rod 83 and thus simultaneously rotating the shaft 16 with respect to the lever 7.

In general we have provided a straightforward, economical means for metering fuel in the desired amounts over a very wide range relatively without increasing the pressure unduly nor decreasing it below a minimum atomizing pressure. The mechanism is capable of comprehensive and accurate adjustment and is readily adapted to the instantaneous requirements of operation and also to the general environment changes normally encountered.

We claim:

1. A fuel burning system comprising a plurality of external combustion fuel burner nozzles, a variable speed fuel pump having a high pressure side and a low pressure side, a fuel conduit connecting the high pressure side of said fuel pump and said nozzles, a variable device for releasing fuel from said conduit to the low pressure side of said pump, a valve in said conduit for controlling fuel flow to one of said nozzles, an internal combustion engine for driving said pump, a movable controller for varying the speed of said engine and hence of said fuel pump, and a connection to said controller for varying said releasing device and for operating said valve in accordance with the position of said controller.

2. A fuel burning system comprising an external combustion fuel burner nozzle, a variable speed fuel pump having a high pressure side and a low pressure side, a fuel conduit connecting the high pressure side of said fuel pump and said nozzle, a variable device for releasing fuel from said conduit to the low pressure side of said pump, an internal combustion engine for driving said pump, a movable controller for varying the speed of said engine, and a connection to said controller for varying the speed of said engine.

for varying said releasing device in accordance with the position of said controller.

3. A fuel burning system comprising a first nozzle, a second nozzle, a fuel pump, a main fuel conduit connecting said fuel pump and said first nozzle, a branch fuel conduit connecting said main fuel conduit and said second nozzle, a first device openable in response to a predetermined high fuel pressure in said main fuel conduit for releasing fuel from said main fuel conduit, a second device openable in response to a predetermined low fuel pressure in said branch fuel conduit for releasing fuel from said branch fuel conduit, and a valve for blocking and unblocking communication from said main fuel conduit to said branch fuel conduit.

4. A fuel burning system comprising a nozzle body having a fuel conducting bore therein, a nozzle tip mounted on said body in communication with said bore, a fuel conduit at one end connected to said body in communication with said bore, a first valve in said body for controlling fuel flow through said bore, said first valve having differential areas subject to pressure of said fuel, a first spring for urging said first valve closed, a fuel pump for supplying fuel under pressure to the other end of said conduit, a second valve for releasing fuel from said conduit adjacent said other end, a second spring for urging said second valve closed, and a cam for gradually varying the force of said second spring gradually to vary the pressure of fuel in said conduit above and below the values at which the differential areas of said first valve are effective to overcome said first spring.

5. A fuel burning system comprising a nozzle body, a nozzle tip mounted on said body, means including a long conduit for supplying said nozzle body and said nozzle tip with fuel, a valve in said nozzle body adjacent said nozzle tip responsive to fuel pressures below a first predetermined pressure for abruptly preventing said fuel from flowing to said nozzle and responsive to fuel pressure above a second predetermined pressure for abruptly permitting said fuel to flow to said nozzle, and a cam actuated relief valve in said conduit remote from said nozzle body for gradually varying the pressure of said fuel from a pressure below said first predetermined pressure to a pressure above said second predetermined pressure.

6. A fuel burning system comprising a first nozzle, means for supplying said nozzle with fuel under pressure, a relief valve on said supplying means, a spring urging said relief valve closed against said fuel pressure, means for moving said spring between two positions correspondingly to vary the pressure of said fuel from minimum to maximum, a second nozzle, means for conducting fuel from said supplying means to said second nozzle, and means for varying the pressure of fuel supply by said supplying means and for simultaneously holding said spring in a position corresponding to said maximum pressure.

7. A fuel burning system comprising a first nozzle, a second nozzle, means for supplying said nozzles with fuel under pressure, means for blocking the supply of fuel to said second nozzle, a first relief valve on said supplying means in advance of said blocking means, a first spring urging said first relief valve closed against and fuel pressure, means for moving said first spring into successive positions correspondingly to vary the pressure of fuel supplied to said first nozzle, means for unblocking the supply of fuel to said second nozzle when said first spring moving

11

means is in one of said positions, a second relief valve on said supplying means after said blocking means, a second spring urging said second relief valve closed against said fuel pressure, and means for moving said second spring into successive position correspondingly to vary the pressure of fuel supplied to both of said nozzles and for holding said first spring in said one of said positions.

8. A fuel burning system comprising a first nozzle, means for supplying fuel under pressure, a first conduit for conducting fuel from said supplying means to said first nozzle, a first valve responsive to pressure of said fuel in said first conduit for releasing fuel from said first conduit, means for gradually closing said first valve, a second nozzle, a second conduit for conducting fuel from said supplying means to said second nozzle, means for blocking said second conduit, means effective at a predetermined point in the gradual closing of said first valve for abruptly unblocking said second conduit and for holding said first valve at said point, and a second valve responsive to pressure of said fuel in said second conduit for releasing fuel from said second conduit.

9. A fuel burning system comprising a first nozzle, means for supplying fuel under pressure, a first conduit for conducting fuel from said supplying means to said first nozzle, a first valve urged toward open position by pressure of fuel in said first conduit for releasing fuel from said first conduit, a spring for urging said valve toward closed position, a second nozzle, a second conduit for conducting fuel from said supplying means to said second nozzle, a valve when closed blocking said second conduit, and a cam for increasing the force of said spring and for opening said second valve independently of said fuel pressure.

10. A fuel burning system comprising a first nozzle, a second nozzle, a conduit for supplying fuel to said first nozzle and to said second nozzle, means for blocking said conduit in advance of said second nozzle, a first pressure responsive device for releasing fuel from said conduit in advance of said blocking means, means for operating said first device for controlling the pressure of said fuel to establish discharge of fuel from said first nozzle at a predetermined rate, means for opening said blocking means to supply fuel both to said first nozzle and to said second nozzle, a second pressure responsive device for releasing fuel from said conduit beyond said blocking means, and means for operating said second device for controlling the pressure of said fuel to establish discharge from both of said nozzles at said predetermined rate.

11. A fuel burning system comprising a first nozzle, a second nozzle, means for supplying fuel to said first nozzle, a first device responsive to pressure of said fuel for regulating the pressure of said fuel supplied to said first nozzle between a predetermined low pressure and a predetermined high pressure correspondingly to vary the discharge of said fuel from said first nozzle between a predetermined low rate and a predetermined high rate, means for supplying fuel to said second nozzle, a second device responsive to

12

pressure of said fuel for regulating the pressure of said fuel supplied both to said first nozzle and to said second nozzle at said predetermined low pressure to establish the total discharge of said fuel from both of said nozzles considered together at said predetermined high rate, and means for alternatively supplying fuel to said first device and said first nozzle alone or for supplying fuel to both of said nozzles and said devices together.

12. For use in a fuel burning system, a housing, a duct for fuel under pressure in said housing, a cam shaft in said housing, a relief valve in said duct, a spring for said relief valve, a cam on said cam shaft for varying said spring, a nozzle conduit in said housing opening into said duct, a blocking valve for controlling communication between said conduit and said duct, and a cam on said cam shaft for operating said blocking valve.

13. For use in a fuel burning system, a housing, a duct for fuel under pressure in said housing, a cam shaft in said housing, a plurality of relief valves in said duct, a nozzle conduit in said housing opening into said duct between said relief valves, a blocking valve for controlling communication between said conduit and said duct, springs for said relief valves, and cams on said cam shaft for varying said springs in succession and for operating said blocking valve.

14. A fuel burning system comprising a first nozzle, a source of fuel under pressure, a first conduit for supplying said first nozzle with fuel from said source, a first valve for releasing fuel from said first conduit, a first cam movable through a first range gradually to close said first valve to a predetermined position and through a second range to hold said first valve in said position, a second nozzle, a second conduit for supplying said second nozzle with fuel from said source, a second valve for admitting fuel to said second nozzle, a third valve for releasing fuel from said second conduit, a second cam movable through a first range gradually to close said third valve to a predetermined position as said first cam moves through said second range, and cam means for opening said second valve substantially as said first cam moves from said first range to said second range.

ROBERT L. HARRIS.
MARCUS LOTHROP.
